LOCKING ARRANGEMENT FOR PHOTOGRAPHIC APPARATUS

Filed Oct. 30, 1967

tions 14, 16 is provided with an aperture at 32, into which the shaft 26 and the compression spring 30 protrude in operating position. The section members 14, 16 are recessed at 34, 36, respectively, for purposes which will presently be made clear. A keying member means is indicated generally at 38 and comprises an extended shaft portion 40, lug members 42, 44, and a detent button 20. The extended shaft portion 40 has a diameter of such magnitude so as to fit closely within the recess 28 in rotating engagement. The cover member 24 is suitably apertured at 46, the periphery of the aperture 46 including diametrically opposed raised arcuate stop elements 48, 50 and diametrically opposed enlarged arcuate recesses at 52, 54.

Completing the description of the practical embodiment shown in FIG. 2, a sliding contact is indicated at 56. Electrical isolation between the body member 22 and the sliding contact 56 is provided by a vulcanized fiber paper insulation element 58. One terminal member for the battery in the compartment 12 is shown at 60 (FIG. 2) and is arranged to make contact with the sliding contact member 56. The other terminal member for the battery in the compartment 12 is indicated partially in phantom section at 62; this terminal member 62 bears against the shaft 26, which is electrically common with the camera body.

OPERATION

In the normal carrying position of the movie camera, the handle and battery compartment 12 is tucked in against the camera body, so that the whole forms a conveniently handled, substantially rectangular unit, the compartment 12 being locked in closed position by means of the locking arrangement of this invention.

As depicted in the schematic of FIG. 4, the compartment 12 (shown in phantom section) by definition is in the closed position. It will be noted that lugs 42, 44 of the keying member 38 are seated in recesses 34, 36 and are in contiguous relationship with arcuate raised stop elements 48, 50. The spring means 30 bears against the end of the shaft portion 40, forcing lugs 42, 44 into the recesses 34, 36. The raised stop elements 48, 50 have a slight ramp (approximately 15°) in the axial direction of the keying element 38 which permits the lugs 42, 44 to be wedged tight so as to hold the compartment 12 immobile.

When it is desired to rotate the compartment 12 to the extended position as defined in FIG. 5, the button 20 is depressed and the compartment 12 is rotated slightly. This movement causes lug 42 of the keying element 38 to ride on the raised arcuate stop element 48 of the cover 24 as compartment 12 is rotated. At the same time, the lug 44 of the keying element 38 rides on the arcuate stop element 50 of the cover 24. The spring means 30 continues to press against the bottom of the extended shaft portion 40.

As the compartment 12 continues to rotate, lugs 42, 44 reach the end of their travel on arcuate stop elements 48, 50 and drop into the arcuate recesses 52, 54. This extended position is depicted in FIG. 5. As is indicated in the diagram of FIG. 4, the compartment 12 has been displaced through 100° of angular rotation. In the extended position, the handle 12 cannot be further advanced in the forward direction because of the geometry of the compartment 12 and the cover members 22, 24. Return in the reverse direction is also prohibited by the locking action afforded by lugs 42, 44 which wedge tightly against the arcuate stop elements 48, 50 (FIG. 5).

In an analogous manner, the handle 12 may be returned from the extended position of FIG. 5 to the closed position of FIG. 4, merely by pressing the detent button 20 and rotating the handle 12, thus moving the lugs 42, 44 out of the recesses 52, 54 and permitting the operator to rotate member 12 in the direction of the next locked position.

The invention has been described in detail with parti-

cular reference to preferred embodiments thereof, but it will be understood that variations and modifications can be effected within the spirit and scope of the invention as described hereinabove and as defined in the appended claims.

I claim:

1. A detent device comprising:

- (a) support means having an aperture with a plurality of arcuate recesses and a plurality of raised stop elements arranged alternately around the periphery of said aperture;
- (b) keying means comprising a plurality of lug members;
- (c) detent actuating means adapted to fit slidably and rotatably into said aperture;
- (d) a handle member rotatably mounted on said support means, substantially coaxially with said aperture, and having a plurality of recessed openings each adapted to receive a respective one of said lug members; and
- (e) biasing means on said support means adapted to exert a biasing force against said keying means, urging said lug members into said recesses, whereby the detent actuating means enables manual displacement of said lug members out of said recesses to permit said lug members to be rotatably displaced until the lug members are in locking engagement with said stop elements respectively.

2. A detent device comprising:

- (a) support means having an aperture with a plurality of arcuate recesses and a plurality of raised stop elements arranged alternately around the periphery of said aperture;
- (b) keying means comprising a plurality of lug members and detent actuating means adapted to fit slidably and rotatably into said aperture;
- (c) a handle member rotatably mounted on said support means, substantially coaxially with said aperture, and having a plurality of recessed openings each adapted to receive a respective one of said lug members; and
- (d) spring means on said support means adapted to exert a biasing force against said keying means, urging said lug members into said recesses, whereby the detent actuating means enables manual displacement of said lug members out of said recesses to permit said lug members to be rotatably displaced until the lug members are in locking engagement with said stop elements respectively.

3. A detent device for a handle arranged on a movie camera or the like and adapted to be movable into successive locked positions comprising:

- (a) a support member on said movie camera having an aperture and a plurality of recesses and raised stop elements arranged alternately around the periphery of said aperture;
- (b) a keying member comprising a plurality of lug members and detent actuating means, the detent actuating means being adapted to fit into said aperture and extend externally of said support member;
- (c) a handle member rotatably mounted on said support member, substantially coaxially with said aperture, and having a plurality of recessed openings therein adapted to receive said plurality of lug members in locking engagement;
- (d) spring means on said support member adapted to exert a biasing force against said keying member, whereby in a predetermined locked position, said lug members are in contiguous engagement with a cooperating pair of stop elements, to provide locking positions, respectively, the detent activating means enabling manual displacement of said lug members to permit said lug members to be rotatably displaced along said stop elements until the lug members fall into the adjacent recesses and are moved

into subsequent locking engagement with a pair of said stop elements.

4. A detent device for a handle arranged on a movie camera or the like and adapted to be movable into two successive locked positions comprising:

- (a) support means on said movie camera, said support means having an aperture therein and a plurality of recesses and raised stop elements arranged alternately around the periphery of said aperture, the angular displacement between adjacent edges of said stop elements measured in the direction of rotation being substantially 100°;
- (b) a keying member comprising a plurality of lug members and a detent actuating means integral therewith, the detent actuating means being adapted to fit into said aperture and extend externally of said support member;
- (c) a handle member rotatably mounted on said support member, coaxial with said aperture, and adapted to be displaced between said two locked positions, said handle member having a plurality of recessed openings therein adapted to receive said plurality of lug members so that in locking engagement, said keying member and said handle member move in unison;
- (d) helical spring means mounted on said support member adapted to exert a biasing force against said keying member, whereby in either one of said locked positions, said lug members are in contiguous engagement with a cooperating pair of stop elements, respectively, the detent actuating means being adaptable for manually displacing said lug members to permit said lug members to be rotatably displaced along said raised stop elements until the lug members fall into the subsequent recesses and are moved into locking engagement with the succeeding stop elements.

5. A detent device for a handle arranged on a movie camera or the like and adapted to be movable into two successive locked positions comprising:

- (a) support means on said movie camera, said support means having an aperture therein and a plurality of recesses and raised stop elements arranged alternately around the periphery of said aperture, the angular displacement between adjacent edges of said

stop elements measured in the direction of rotation being substantially 100°;

- (b) a keying member comprising a plurality of lug members and detent actuating means integral therewith, the detent actuating means being adapted to fit into said aperture and extend externally of said support member;
- (c) a shaft mounted on said support means, said shaft being axially recessed;
- (d) a handle member rotatably mounted on said shaft substantially coaxial with said aperture, said handle member having a plurality of recessed openings therein adapted to receive said lug members so that in locking engagement, said keying member and said handle member move in unison;
- (e) helical spring means mounted in the axial recess of said shaft, adapted to exert a biasing force against said keying member, whereby in either one of said locked positions, the said lug members rest in said recesses in contiguous engagement with a cooperating pair of stop elements, respectively, the detent actuating means being adaptable for manually displacing said lug members so that they may be rotatably displaced along said raised stop elements until the lug members fall into the subsequent recesses in locking engagement with said stop elements.
